UNITED STATES PATENT OFFICE.

ASA M. BUNN, OF KANSAS CITY, MISSOURI, ASSIGNOR OF ONE-HALF TO FREDERICK J. CLOSE, OF KANSAS CITY, KANSAS.

RAILWAY ROAD-BED.

1,210,043.

Specification of Letters Patent. Patented Dec. 26, 1916.

Application filed January 7, 1915, Serial No. 929. Renewed June 5, 1916. Serial No. 101,869.

To all whom it may concern:

Be it known that I, ASA M. BUNN, a citizen of the United States, residing at Kansas City, in the county of Jackson and State 5 of Missouri, have invented a certain new and useful Improvement in Railway Road-Beds, of which the following is a specification.

My invention relates to improvements in 10 railway road beds.

The object of my invention is to provide a railway road bed from which the ordinary wooden cross ties are eliminated, and which will have greater durability, will require less 15 repairing, and which will possess greater resiliency than the usual road bed which employs wooden cross ties.

In the accompanying drawing which illustrates the preferred embodiment of my invention, Figure 1 is a cross sectional view of 20 my improved road bed. Fig. 2 is a plan view of the same shown partly broken away.

Similar reference characters designate similar parts in the different views.

25 In the preferred form of my invention, a holding trench, preferably having a rigid bottom and side walls and composed of a solid material, such as concrete material 1, is provided. Upon the bottom of the trench 30 1 is placed a bed of sand 2, upon which rests a foundation 3, which is, preferably, of a resilient material, such as asphalt or other solid bituminous material. Upon the foundation 3 are supported horizontal cross 35 ties, preferably comprising flat steel plates 4 having upwardly and inwardly turned outer ends 5 which respectively engage the side walls of the trench 1, whereby lateral movement of the cross ties upon its foundation is 40 prevented relatively to the trench. Upon the cross ties 4 are mounted the usual T rails 6, the outer portions of the bases 7 of which are respectively overlapped and embraced by the flanges or upwardly and inwardly turned ends 5 of the cross ties 4.

45 Clamping plates 8 are mounted upon the cross ties 4 and respectively overlap the joints 9 between said cross ties. The outer ends of the clamping plates 8 overlap and 50 embrace respectively the inner portions of the bases 7 of the rails 6. Vertical bolts 10 extend through the cross ties 4 and the clamping plates 8, said bolts being provided with nuts 11, by means of which the clamping plates 8 are firmly secured to the cross

ties 4. Upon the cross ties 4 and clamping plates 8, between the rails 6 may be placed a bed of sand 12 upon which may be mounted paving blocks or stones 13. Between the side walls of the trench 1 and the outer sides 60 of the rails 6 may be placed asphaltic material 14.

In laying my improved road bed, the concrete trench 1 is molded between suitable forms upon the graded right of way, or in a 65 suitable ditch cut in a street, when the road bed is laid in the street of a city. After the concrete has sufficiently hardened, the bed of sand 2 is placed in the trench 1, and upon this sand bed is placed the foundation 3, 70 which may be tamped asphaltic material, the upper side of the foundation being suitably surfaced. The metal base plates or cross ties 4 are then placed edge to edge within the trench 1 upon the asphaltic foundation 3, 75 following which the rails 6 are slipped into position upon the cross ties 4 with the inwardly and upwardly turned ends 5 thereof overlapping and embracing the outer portions of the bases 7 of said rails. The clamping plates 8 are then mounted upon the cross ties 4 in positions in which the joints 9 will be overlapped, the ends of the clamping plates 8 being arranged to embrace and hold the inner portions of the bases 7 of the rails 6, 80 85 the bolts 10, which have been previously inserted, heads down, through the cross ties 4, being inserted through holes provided therefor in the clamping plates 8. The nuts 11 are then mounted on the bolts 10, so as 90 to tightly clamp the plates 8 to cross ties 4, thereby securely holding the rails 6 in their proper positions.

The width of the trench 1 is such that the cross ties 4 neatly fit between the walls thereof, thereby holding the cross ties, and with them the rails 6 and clamping plates 8 from lateral movement relatively to the trench. The trench also securely retains the asphaltic foundation 3 and the sand bed 2 in their 95 proper positions. The clamping plates 8 in addition to their function of securing the rails to the cross ties, also serve to strengthen and make more rigid said cross ties, and serve also to seal the joints 9 between the cross ties, thereby preventing the passage downwardly therebetween of moisture and also preventing the weight placed on the rails from forcing any of the asphaltic material 3 upwardly between the cross ties 4. 100 105 110

After the rails have thus been mounted in and secured in their appropriate positions, the bed of sand 12 may be placed upon the cross ties between the rails, following which, 5 if desired, the paving blocks 13 may be mounted thereupon. The asphaltic material 14 is then placed between the rails and the side walls of the trench, thus sealing the trench from the access of moisture from the 10 surface of the road bed to the cross ties and to the foundation 3.

A foundation of asphaltic material, such as Trinidad asphalt, possesses great resiliency, much more than that which is possessed by wood sufficiently hard to render it 15 suitable for service as railroad ties. The final residue from the manufacture of crude oil, known in the commercial world under different titles, such as "Sarco" and "Texico" 20 serves admirably as a bituminous foundation for the metallic cross ties which are employed in my road bed construction. The materials above named are impervious to moisture and are, therefore, not affected by 25 freezing weather.

By fitting the cross ties 4 within a trench which holds them from lateral movement, the danger of the rails spreading, and the liability to wrecks due to this cause, is 30 wholly eliminated in my improved road bed.

I do not limit my invention to the structure herein described and illustrated, as modifications, within the scope of the appended claims, may be made without departing 35 from the spirit of my invention.

What I claim is:—

1. In a railway road bed, the combination with a holding trench, of a resilient foundation in said trench, cross ties mounted on 40 said foundation and having their ends engaged by the side walls of said trench, and rails supported by and secured to said cross ties.

2. In a railway road bed, the combination 45 with a holding trench, of a resilient foundation in said trench, cross ties mounted on said foundation and held by the side walls of said trench from lateral movement in said trench and provided with upwardly and inwardly turned ends, and rails supported by said cross ties and having their bases overlapped at the outer sides thereof by said inwardly turned ends.

3. In a railway road bed, the combination 55 with a holding trench, of a bituminous foundation in said trench, cross ties mounted on said foundation and held from lateral movement by the side walls of said trench, and rails supported by and secured to said cross ties.

4. In a railway road bed, the combination 60 with a holding trench, of a foundation of asphaltic material in said trench, cross ties mounted on said foundation and held from lateral movement by the side walls of said

trench, and rails supported by and secured to said cross ties.

5. In a railway road bed, the combination with a holding trench, of a resilient foundation in said trench, cross ties mounted on 70 said foundation and held by the side walls of said trench from lateral movement relative thereto, rails supported by and secured to said cross ties, and clamping plates secured to said ties and respectively overlapping the joints between said ties and having their outer ends respectively overlapping and embracing the bases of said rails. 75

6. In a railway road bed, the combination with a holding trench, of a resilient foundation in said trench, cross ties mounted on 80 said foundation and held by the side walls of said trench from lateral movement relative thereto, and provided with inwardly and upwardly turned ends, rails supported 85 by said cross ties and having the outer portions of their bases respectively overlapped and embraced by said upwardly turned ends, and clamping plates secured to said ties and respectively overlapping the joints between 90 said ties and having their outer ends respectively overlapping and embracing the inner portions of the bases of said rails.

7. In a railway road bed, the combination with a holding trench, of a foundation of 95 bituminous material in said trench, cross ties mounted on said foundation and held by the side walls of said trench from lateral movement relative thereto, rails supported by and secured to said cross ties, and clamping plates secured to said ties and respectively overlapping the joints between said ties and having their outer ends respectively overlapping and embracing the bases of said rails. 100

8. In a railway road bed, the combination with a holding trench, of a foundation of asphaltic material in said trench, cross ties mounted on said foundation and held by the side walls of said trench from lateral movement relative thereto, rails supported by 105 and secured to said cross ties, and clamping plates secured to said ties and respectively overlapping the joints between said ties and having their outer ends respectively overlapping and embracing the bases of said rails. 110

9. In a railway road bed, the combination with a holding trench, of a foundation of bituminous material in said trench, cross ties mounted on said foundation and held by the side walls of said trench from lateral movement relative thereto, and provided with inwardly and upwardly turned ends, rails supported by said cross ties and

having the outer portions of their bases respectively overlapped and embraced by said upwardly turned ends, and clamping plates secured to said ties and respectively overlapping the joints between said ties and hav- 115 120 125 130

ing their outer ends respectively overlapping and embracing the inner portions of the bases of said rails.

10. In a railway rod bed, the combination
5 with a holding trench, of a foundation of asphaltic material in said trench, cross ties
mounted on said foundation and held by the
side walls of said trench from lateral move-
ment relative thereto, and provided with in-
10 wardly and upwardly turned ends, rails sup-
ported by said cross ties and having the
outer portions of their bases respectively
overlapped and embraced by said upwardly

turned ends, and clamping plates secured to
said ties and respectively overlapping the 15
joints between said ties and having their
outer ends respectively overlapping and em-
bracing the inner portions of the bases of
said rails.

In testimony whereof I have signed my 20
name to this specification in presence of two
subscribing witnesses.

ASA M. BUNN.
